UNITED STATES PATENT OFFICE

149,771

DESIGN FOR A KITCHEN STOVE VENTILATOR

William A. Pledger, San Francisco, Calif.

Application January 10, 1947, Serial No. 136,046

Term of patent 14 years

(Cl. D81—25)

To all whom it may concern:

Be it known that I, William A. Pledger, a citizen of the United States, residing at San Francisco, California, have invented a new, original, and ornamental Design for a Kitchen Stove Ventilator, of which the following is a specification, reference being had to the accompanying drawing, forming part thereof.

The figure is a perspective view of a kitchen stove ventilator, embodying my new design. The back of the ventilator, not shown in the drawing, is substantially plain, and the other end thereof, not shown in the drawing, is substantially like the end shown.

I claim:

The ornamental design for a kitchen stove ventilator, as shown and described.

WILLIAM A. PLEDGER.
